BUILDING BLOCK

Charles E. Johnson, Chicago, Ill., assignor to
 Libbey-Owens-Ford Glass Company, Toledo,
 Ohio, a corporation of Ohio

Application October 2, 1936, Serial No. 103,631

12 Claims.

(Cl. 72—19)

The present invention relates to the construction of walls, especially the exterior walls of buildings, and has for its object the provision of an improved building block for use in the construction of the wall.

The building block herein provided is of composite construction and comprises briefly a body portion formed from a plastic material such as concrete or the like and an ornamental facing 10 therefor which preferably consists of a sheet or plate of opaque glass although ceramic tile may be used in some instances if desired. The ornamental facing is permanently secured to the body portion by an interposed layer of suitable adhesive material such as asphaltic mastic cement and also by novel mechanical fastening means in the form of a metal frame completely surrounding the block and engaging both the ornamental facing and body portion. In constructing a wall 15 with building blocks of the invention, the said blocks are laid up in courses in substantially the same manner as cut stone, granite, or terra cotta, being mechanically anchored to a rear or foundation wall. The vertically and horizontally adjacent blocks are slightly spaced from one another 20 to permit the application of the usual pointing material in the joints.

Other objects and advantages of the invention will become more apparent during the course of 30 the following description when taken in connection with the accompanying drawings.

In the drawings wherein like numerals are employed to designate like parts throughout the same.

Fig. 1 is a front elevation of a portion of a wall constructed in accordance with the invention;

Fig. 2 is a horizontal sectional view through the wall taken substantially on line 2—2 of Fig. 1;

Fig. 3 is a vertical sectional view through the 40 wall taken substantially on line 3—3 of Fig. 1;

Fig. 4 is a perspective view of the metal frame which is used to mechanically secure the ornamental facing to the body portion;

Fig. 5 is a perspective view of a sheet or plate 45 of opaque glass or ceramic tile constituting the ornamental facing for the block;

Fig. 6 is a view of the metal frame showing the braces associated therewith; and

Fig. 7 is a perspective view showing the manner in which the building blocks are anchored to the rear or foundation wall.

In the embodiment of the invention illustrated in the drawings, A designates the rear or foundation wall and B the front or sheathing wall constructed of the improved building blocks provided

by the invention. While the rear wall A is here shown as consisting of conventional bricks or blocks 10 laid in the usual manner with mortar 11, the said wall may be of any other construction.

The building blocks herein provided may be of any desired contour but, as shown in Fig. 1, the said blocks, designated in their entirety by the numeral 12, are rectangular and this is the preferred shape. Each building block is of a composite construction comprising a body portion 13 formed of a plastic material such as concrete or the like and a facing 14 preferably consisting of a sheet or plate of opaque glass although ceramic tile may be employed. The ornamental facing covers the front surface of the concrete body portion and interposed between the said facing and body portion is a layer of suitable adhesive material 15 preferably consisting of asphaltic mastic cement which tends to bind the facing to the body portion while at the same time permitting relative expansion and contraction of said facing and body portion.

Extending entirely around the perimeter of the building block is a metal frame 16, preferably of a 25 rust-proof metal, which engages both the ornamental face plate 14 and the body portion 13 whereby to permanently secure the former to the latter. When constructing a rectangular building block, the metal frame 16 is also rectangular 30 as shown in Fig. 6 and in such case includes the spaced vertical side members 17 and 18 and the horizontal top and bottom members 19 and 20. The side members 17 and 18 consist of flat strips 35 of metal having their forward longitudinal edges turned inwardly as at 21 and 22 respectively (Fig. 4) to provide beads which are adapted to be received within grooves 23 and 24 formed in the opposite side edges of the face plate 14 (Fig. 5).

Each of the side members 17 and 18 has secured 40 to the inner surface thereof a channel member 25 extending substantially the entire length of said side member and including the spaced inwardly directed parallel flanges 26 and 27. The flanges 26 are spaced inwardly of the beads 21 45 and 22 and are adapted to engage the inner surface of the face plate 14 to properly position the said plate within said frame during the construction of the block. The flanges 27 are adapted to be embedded in the body portion 13.

The top and bottom members 19 and 20 of the frame 16 also comprise flat strips of metal of the same width as the side members 17 and 18 and secured to the inner faces thereof are the longitudinally extending angle strips 28 which 55

align and cooperate with the flanges 26 of channel members 25 to properly position the face plate in the frame. While only the opposite side edges of the face plate 14 are here shown as being provided with grooves, it will be appreciated that the top and bottom edges thereof may also be grooved and the top and bottom members 19 and 20 of the metal frame provided with beads to fit in said grooves if desired.

10 In the construction of the building block 12 above described, the two side members 17 and 18 of the metal frame are first associated with either the top or bottom member as shown in Fig. 4, being welded or otherwise suitably secured together. The face plate 14 is then slipped into the open side of the frame, with the beads 21 and 22 on the side members being received within the grooves 23 and 24 in the edges of the face plate, after which the remaining member 20 of the frame is secured to the free ends of said side members by welding or in any other desired manner. When the face plate 14 is properly assembled with the metal frame, the inner surface of said face plate engages the flanges 26 of the channel members 25 and also the angle strip 28.

15 20 25 30 35 40

After the face plate and metal frame have been assembled, they are laid horizontally upon a suitable support with the face plate downwardly. A layer of mastic or other suitable adhesive 15 of the desired thickness is then poured over the back surface of the face plate, after which the concrete or other plastic material forming the body portion 13 is poured over the layer of adhesive. It will be readily apparent that when this is done, the metal frame constitutes a mold or pan into which the adhesive and concrete are poured. Also, that after the concrete has set, the flanges 27 of the side members 17 and 18 of the frame will be firmly embedded therein.

45 50 55 Prior to the pouring of the concrete body portion, however, a plurality of braces 29 may be associated with the frame 16. As shown, these braces are substantially T-shaped in cross section and are adapted to extend vertically when the block is mounted in the wall. In practice, the braces are cemented in place with the mastic, after which the concrete is poured so that the said braces are embedded in both the layer of mastic 15 and body portion 13. These braces act as columns in a building and bear whatever pressure develops so as to take the strain from the concrete as well as from the face plate. The said braces are also formed so as to hold the concrete together in the frame.

60 65 70 75 In constructing a wall from the blocks 12, the said blocks may be laid up in courses as shown in Fig. 1, with the adjacent blocks being slightly spaced from one another to permit the application of a pointing material in the joints. The blocks are also adapted to be mechanically tied to the rear or foundation wall A in the same manner as is done with cut stone, granite, or the like. This may be accomplished by the use of a plurality of strap iron anchors each comprising a flat body portion 30 which is built into the rear or foundation wall A so that it cannot be pulled out.

70 75 The outer end of the body portion 30 of the anchor is split longitudinally to provide the tongues 31 and 32 which are bent in opposite directions at right angles to said body portion. The top and bottom members 19 and 20 of the metal frame 16 are provided with slots 33 and

the concrete body portion 13 is also formed at the top and bottom thereof with openings 34 which register with the slots 33 in the top and bottom members of said frame. When using this type of anchor, it will be seen that each 5 anchor engages two blocks. Thus, the tongue 31 will pass through the slot 33 in the frame and be received in the opening 34 in the top of one block while the tongue 32 will be received in the opening in the bottom of the vertically adjacent 10 block. Ordinary cement mortar 35 can also be used for installing the blocks against the foundation wall. If desired, spacing strips 36 of cork or other suitable material may be arranged in the horizontal joint between vertically adjacent 15 blocks, as shown in Fig. 3, to act as a cushion. These strips terminate inwardly of the outer surfaces of the face plates to provide for the introduction of pointing material 37 in the joints. The pointing material is also placed in the vertical 20 joints between horizontally adjacent blocks.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. A building block of the character described comprising a body portion formed from plastic material, a face plate of vitreous material covering a surface of the body portion and provided with grooves in opposite edges thereof, and a metal frame arranged entirely around said body portion and having portions thereof received within the grooves in the edges of said face plate.

2. A building block of the character described comprising a body portion formed from plastic material, a face plate of vitreous material covering a surface of the body portion, a layer of adhesive material between the face plate and body portion, said face plate being provided with grooves in opposite edges thereof, and a metal frame arranged entirely around said body portion and having portions thereof received within the grooves in the edges of said face plate.

3. A building block of the character described comprising a body portion formed from concrete, a face plate covering a surface of the body portion and provided with grooves in opposite edges thereof, and a metal frame arranged entirely around the body portion and having portions thereof received within the grooves in the edges of said face plate and other portions embedded in said body portion.

4. A building block of the character described comprising a body portion formed from concrete, a face plate covering a surface of the body portion, a layer of adhesive material between the face plate and body portion, said face plate being provided with grooves in opposite edges thereof, and a metal frame arranged entirely around the body portion and having portions thereof received within the grooves in the edges of said face plate and other portions embedded in said body portion.

5. A building block of the character described comprising a body portion formed from plastic material, a face plate covering a surface of the body portion and provided with grooves in opposite edges thereof, a metal frame arranged entirely around said body portion and having portions thereof received within the grooves in the edges of said face plate, and means carried by the metal frame and engaging the inner surface

of the face plate for positioning the said face plate relative to said frame.

6. A building block of the character described comprising a body portion formed from plastic material, a face plate covering a surface of the body portion, a layer of adhesive material between the face plate and body portion, said face plate being provided with grooves in opposite edges thereof, a metal frame arranged entirely around said body portion and having portions thereof received within the grooves in the edges of said face plate, and means carried by the metal frame and engaging the inner surface of the face plate for positioning the said face plate relative to said frame.

7. A building block of the character described comprising a body portion formed from concrete, a face plate covering a surface of the body portion and provided with grooves in opposite edges thereof, a metal frame arranged entirely around the body portion and having portions thereof received within the grooves in the edges of said face plate and other portions embedded in said body portion, and means carried by the metal frame and engaging the inner surface of the face plate for positioning the said face plate relative to said frame.

8. A building block of the character described comprising a body portion formed from concrete, a face plate covering a surface of the body portion, a layer of adhesive material between the face plate and body portion, said face plate being provided with grooves in opposite edges thereof, a metal frame arranged entirely around the body portion and having portions thereof received within the grooves in the edges of said face plate and other portions embedded in said body portion, and means carried by the metal frame and engaging the inner surface of the face plate for positioning the said face plate relative to said frame.

9. A building block of the character described comprising a body portion formed from plastic material, a face plate covering a surface of the body portion and provided with grooves in op-

posite edges thereof, a frame comprising a plurality of flat metal strips arranged entirely around the body portion, certain of said strips having inturned longitudinal edges which are received within the grooves in the edges of said face plate, and means carried by other of said strips and embedded in said body portion.

10. A building block of the character described comprising a body portion formed from plastic material, a face plate covering a surface of the body portion and provided with grooves in opposite edges thereof, a layer of adhesive material between the face plate and body portion, a frame comprising a plurality of flat metal strips arranged entirely around the body portion, certain of said strips having inturned longitudinal edges which are received within the grooves in the edges of said face plate, and means carried by other of said strips and embedded in said body portion.

11. A building block of the character described comprising a body portion formed from concrete, a face plate covering a surface of the body portion and provided with grooves in opposite edges thereof, a frame comprising a plurality of flat metal strips arranged entirely around the body portion, certain of said strips having inturned longitudinal edges which are received within the grooves in the edges of said face plate, and means carried by other of said strips and embedded in said body portion.

12. A building block of the character described comprising a body portion formed from concrete, a face plate covering a surface of the body portion and provided with grooves in opposite edges thereof, a layer of adhesive material between the face plate and body portion, a frame comprising a plurality of flat metal strips arranged entirely around the body portion, certain of said strips having inturned longitudinal edges which are received within the grooves in the edges of said face plate, and means carried by other of said strips and embedded in said body portion.

CHARLES E. JOHNSON. 45
